UNITED STATES PATENT OFFICE

2,399,910

WHEELED TOY

Asa B. Carmichael, Tujunga, Calif.

Application November 15, 1945, Serial No. 628,879

3 Claims. (Cl. 46—105)

The present invention relates to a new and useful improvement in toys and more particularly to a toy mounted on wheels adapted to be pulled along the ground and embodying the provision of an animated horse and human figure operated from the wheels of the toy.

An important object of the invention is to provide a toy of this character representing an animated horse and an animated human figure, such as an intimation cowboy suitably connected to the nose of the horse to simulate the action of the horse in nudging or pushing the human figure forwardly during the forward travel of the horse and in which the legs of the human figure and the tail and ears of the horse are operatively connected to the wheels on which the horse is mounted for the actuation thereof as the toy is moved over the ground.

A further object of the invention is to provide a toy of this character of simple and practical construction, which effectively simulates a walking action of the human figure as the toy is drawn over the ground, which may be manufactured at relatively low cost and which is otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a longitudinal sectional view through the bodies of the horse and human figure.

Figure 3 is a horizontal sectional view taken through the legs of the horse substantially on a line 3—3 of Figure 1.

Figure 4 is a vertical transverse sectional view taken on a line 4—4 of Figure 1.

Figure 5 is a vertical sectional view through one of the legs of the human figure, and

Figure 6 is an enlarged view in elevation of the pulley forming the knee joint of the legs.

Figure 7 is an enlarged fragmentary sectional view of the oscillating mounting for one of the ears of the animal.

Referring now to the drawings in detail wherein for the purpose of illustration I have disclosed a preferred embodiment of the invention. The numeral 5 designates an imitation animal, such as a horse or the like, and the numeral 6 designates an imitation human figure preferably clothed or ornamented to represent a cowboy.

The body and head of the horse 5 is hollow and the body and head of the human figure 6 is likewise of hollow construction.

The front and rear legs 7 and 8 of the toy horse are rigidly connected to the body, the front legs 7 being connected by a transverse axle 9 to which a pair of wheels 10 and a pair of pulleys 10a are secured and the rear legs 8 are similarly connected by a transverse axle 11 on which the ground wheels 12 are journaled, the wheels 10 and 12 supporting the animal for movement along the ground.

The rear of the body of the human figure 6 is cemented or otherwise suitably connected to the nose 13 of the animal so as to provide a rigid connection therebetween.

The central portion of the body 5 of the animal is provided with a pair of spaced parallel vertically extending posts 14, one of the posts having a disk 15 and pulley 16 secured for rotation as a unit at opposite sides of the post by means of a pin 17 while the other post likewise has a disk 18 and pulley 19 similarly secured thereon by means of a pin 20.

25 A drive belt 21 operatively connects one of the front pulleys or wheels 10a with the pulley 16 and a similar drive belt 22 connects the other front wheel or pulley 10a with the pulley 19. Accordingly, both sets of pulleys mounted in the body of the horse are rotated by the wheels 10 and the disks and pulley 15 and 16 and the disks and pulley 18 and 19 are respectively connected to each other for the simultaneous rotation thereof.

35 A pin 23 is attached eccentrically to the inside of the pulley 16 to which one end of a flexible cord or other flexible member 24 is attached and which extends forwardly through the body of the horse and over a double pulley 25 rotatably mounted in the head of the horse, the cord then extending downwardly through the nose 13 of the horse and into the lower portion of the body of the imitation figure 6 and around a double pulley 26 journaled in the lower portion of the body

45 of the imitation figure. The other end of the cord 24 then extends downwardly through the left thigh 27 of the human figure and is connected eccentrically to a pulley 28 which forms the knee joint for the lower left leg 29 of the human figure. The pulleys 26 and 28 are journaled respectively at the upper and lower ends of a rigid rod or brace 30 extending through the thigh 27 and a rigid rod or brace 31 extends downwardly in the lower leg portion 29. The rods 30 and 31 are covered by suitable padding 32 as shown in

50 55

detail in Figure 5 of the drawings to form flexible legs for the human figure which are bendable at the knee joint 28.

The disk 15 is likewise provided with an eccentric pin 33 positioned in a side thereof diametrically opposite from the pin 23 and to which one end of a cord or other flexible member 34 is attached which likewise extends over the pulley 25 and downwardly over the pulley 26 in the imitation figure 6 and thence downwardly through the right front leg 35 and connected eccentrically to a pulley 36 at the knee joint thereof. The leg 34 is similarly provided with rigid brace rods 37 and 38 and otherwise is similarly constructed to the left leg.

Accordingly, as the toy is drawn over the ground the pulleys 18 and 19 will be rotated by the wheels 10 whereby to alternately cause a pulling force exerted on the cords 24 and 34, and thus to alternately raise and lower the legs of the imitation human figure to represent a walking action.

The outer surface of the disk 18 is provided with an eccentric pin 39 to which one end of a cord or other flexible member 40 is attached and which extends upwardly and rearwardly in the body of the animal 5 for attaching to the inner end of a bell crank lever 41 which is pivoted on a pin 42 at the rear of the body of the animal and projects upwardly and outwardly therefrom, the outer end of the lever 41 being constructed to represent the tail 43 of the animal.

The ears 44 of the animal are secured to the ends of a shaft 44 journaled in the head thereof and secured to the shaft on the inside of the head of the animal is a pulley 46 over which is trained one end of a cord or flexible member 47 and secured to said pulley. The other end of the cord 47 is attached to a pin 48 which projects from a pulley 19 at a side thereof diametrically opposite from the pin 39.

Accordingly, the tail 43 and ears 44 of the animal are operated by the cords 40 and 47, respectively, as the disk and pulley 18 and 19 are rotated during the travel of the animal along the ground.

In view of the foregoing description taken in conjunction with the accompanying drawings it is believed that a clear understanding of the construction, operation and advantages of the device will be quite apparent to those skilled in the art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim:

1. A toy comprising an animated toy animal and an animated toy human figure, wheels supporting the animal, and means for operating the moving parts of the animal, operating connections between said means and the moving parts of the figure, and a driving connection between said wheels and means, said means and operating connections being completely concealed in said animal and figure.

2. A toy comprising a wheel supported toy animal and a toy walking human figure, said figure being attached to the head of the animal for movement as a unit, said animal including pivoted ears and a pivoted tail and said figure including pivoted legs, and belt and pulley drive means operatively connecting the wheels of the animal to said pivoted elements for actuation thereof upon a movement of the toy over the ground.

3. A toy comprising a wheel supported toy animal and a toy walking human figure, said figure being attached to the head of the animal for movement as a unit, said animal including pivoted ears and a pivoted tail and said figure including pivoted legs, a plurality of pulleys rotatably mounted in the animal, a belt drive between the wheels of the animal and said pulleys, and flexible means operatively connecting the pulleys with the pivoted elements of the animal and figure for actuating said elements upon a movement of the toy over the ground.

ASA B. CARMICHAEL.
